UNITED STATES PATENT OFFICE.

ORAZIO MILLAURO, OF LONDON, ENGLAND.

WINDOW LATCH.

Application filed December 18, 1926, Serial No. 155,654, and in Great Britain October 25, 1926.

This invention relates to improvements in window latches for sliding windows of the kind adapted to secure the window in any desired position by the separation of the 5 two sashes.

In such devices as heretofore proposed a bracket has been fixed to the lower sash and provided with means for providing a direct thrust only on the upper sash.

10 According to my invention means are provided for giving a direct thrust on the upper sash and on the beading of the window frame. Furthermore the device is provided with means for preventing movement of 15 either sash when in the fixed position.

The window latch which forms the subject of this invention comprises an open-ended box-like bracket adapted to be secured transversely to the head of the lower frame.

20 In this bracket slide two blocks mounted on the two parts of a right- and left-handed screw-threaded rod rotatable in the bracket, the outer block having pivoted to one end an extension with a cam surface and the 25 inner block having a transverse lug or projection on one face.

The cam faced extension of the outer block is adapted to bear against the adjacent style of the upper sash, and the transverse lug on the inner block is adapted to bear against the innermost beading of the side frame in which the lower sash slides.

30 By placing the window sashes in any desired position and rotating the screw-threaded rod by any suitable means, the two blocks are forced apart thus holding the window firmly. If an attempt is now made to raise or lower either sash of the window, the extension with the cam surface will turn 40 on its pivot and latch the window, preventing movement thereof.

My invention is illustrated in the accompanying drawings, in which:—

Figure 1 shows the device with the blocks 45 on the screw-threaded rod separate from the bracket in which they slide;

Figure 2 is a partly sectional plan of the upper and lower sashes showing the latch in position and one means for rotating the 50 screw-threaded rod; and

Figure 3 is a front elevation of Figure 2 showing alternative means for rotating the screw-threaded rod.

In these drawings A represents the box-like bracket screwed or otherwise secured 55 by means of the plate A' to the head L of the lower sash, and having in one of its vertical faces a slot A². In this bracket A slides the right- and left-handed screw-threaded rod B, having mounted on the oppositely screw-threaded parts the blocks C and D. The outer block C has pivoted on its outer end at c a cam faced extension C', which, when in operation, bears against the adjacent style E of the upper sash. The 60 inner block D has a transverse lug D' which slides in the slot A² of the bracket A and is adapted to bear against the innermost beading F of the side frame in which the lower sash slides.

70 Each block may be provided with a transverse groove G, so that when the blocks are slid into the bracket A and abut against each other the grooves G are then opposite two holes G' in the bracket through which a small pin or screw may be passed to hold the blocks in the bracket.

75 The end of the rod B may be squared as shown at B' in Fig. 1 and a removable key H (Fig. 2) used to rotate the rod, or a sprocket wheel, over which passes a sprocket chain, may be fitted on the end of the rod B as shown at J and K in Fig. 3.

I claim:

1. A window latch comprising a box-like bracket secured to the head of the lower window sash, two blocks slidably mounted in said bracket and internally screw-threaded, and a right- and left-handed screw-threaded rod engaging said blocks so as to cause them to take a direct thrust on the upper window sash and on the beading of the window frame.

2. A window latch comprising a box-like bracket secured to the head of the lower window sash, two blocks slidably mounted in said bracket and internally screw-threaded, one of said blocks having a transverse lug on one vertical face, a slot in the bracket to accommodate said lug, and a right- and left-handed screw-threaded rod engaging said blocks so as to cause them to take a direct thrust on the upper window sash and on the beading of the window frame.

3. A window latch comprising a box-like bracket secured to the head of the lower

window sash, two blocks slidably mounted in said bracket and internally screw-threaded one of said blocks having a transverse lug on one vertical face, a slot in the bracket 5 to accommodate said lug, the other of said blocks having a pivoted cam-faced extension on its outer end, and a right- and left-

handed screw-threaded rod engaging said blocks so as to cause them to take a direct thrust on the upper window sash and on 10 the beading of the window frame.

In testimony whereof I have hereunto set my hand this 1st day of December, 1926.

ORAZIO MILLAURO.
